BLADED STRUCTURE

Jakob Neufeld, Berlin-Spandau, Germany, assignor to General Electric Company, a corporation of New York

Application November 25, 1940, Serial No. 367,123
In Germany December 9, 1939

2 Claims. (Cl. 253—77)

The present invention relates to bladed structures comprising a plurality of blades securely fastened to a support. Structures of this type are used in the form of bucket wheels for elastic fluid turbines. More specifically, the invention relates to the type of bladed structures or bucket wheels in which a row of buckets is supported on an undercut groove of a disk or drum. To insert the bases of the buckets into the undercut groove, a portion of the support has to be cut away to form a notch. The last bucket or like element to be inserted and supported in the notch has to be firmly anchored therein.

The object of my invention is to provide an improved construction and arrangement of bladed structures of the type above specified whereby a firm support of the element located in the notch is assured. This is accomplished in accordance with my invention by the provision of an arrangement in which the element located in the notch is provided with projections extending laterally and radially therefrom for engaging the inner end faces of adjacent elements. To permit insertion of the notch closing member or block, other elements, preferably spacers between adjacent blades, are made in several parts to permit their insertion subsequent to the insertion of the notch closing element.

For a better understanding of what I believe to be novel and my invention, attention is directed to the following description and the claims appended thereto in connection with the accompanying drawing.

In the drawing Fig. 1 illustrates a front view partly broken away of a bucket wheel for elastic fluid turbines; Fig. 2 is a section along line 2—2 of Fig. 1; Fig. 3 is a top view of Fig. 1; Fig. 4 is a section parallel to the face of the bucket wheel disk; Fig. 5 is a section along line 5—5 of Fig. 4; Fig. 6 is a section along line 6—6 of Fig. 4; and Fig. 7 is a perspective view of the notch block of Fig. 1.

The arrangement comprises a support or disk 10. The disk is machined to form an undercut annular groove 11 with shoulders 12 on opposite sides of the groove to define supports for buckets 13, 14, 15, 16, 17 and 18 are secured to the disk 10. Each bucket has a blade 19 projecting from the support and an undercut base 20 located in the groove 11 of the disk and engaging the shoulders 12, thus forming in substance a dovetail connection. Adjacent buckets are spaced by spacers 21, 22, 23, 24, 25 and 26. The bucket spacers are shaped to conform to the bases of 55

the buckets and to engage the shoulders 12 of the support. To permit insertion of the buckets and the spacers, a portion of the shoulders 12 is cut away, thus forming a notch 27 indicated in dotted lines in Figs. 2 and 3. One of the spacers or buckets which is finally inserted in the notch has to be firmly anchored to remain in position against centrifugal or other forces acting thereon during operation. In the present example the member finally inserted is the spacer 24.

According to my invention the spacer 24 which broadly constitutes a notch block is provided with an inward projection 28 extending circumferentially to engage the end faces of adjacent members (Fig. 4), in the present instance the end faces of the blades 15 and 16. The projection 28 is oval and located in an oval recess 29 formed in the bottom of the groove 11. In order to permit insertion of the notch member or spacer 24, the spacers 23 and 25 between bucket blades 14, 15 and 16, 17 respectively are made in several parts. Each of the spacers 23, 25, as shown in Fig. 5, comprises two halves 30 and 31 and an intermediate or wedge member 32. The halves 30, 31 have outer projections 33, 34 which are turned over to lock the wedge member 32 in position. During assembly the bucket blades and spacers alternately are inserted through the notch 27 and slid along the groove 11. After insertion of the buckets 14 and 17 the succeeding buckets 15 and 16 are inserted and slid towards the buckets 14 and 17 respectively. Thereupon the notch block or spacer 24 is inserted with the projection 28 located in the recess 29. Upon assembly of the notch block 24 the adjacent buckets 15 and 16 are slid towards the spacer 24. Finally, the spacers 23 and 25 are assembled. To this end the halves 30, 31 are inserted into the groove 11 and pushed outward in opposite directions into engagement with the shoulders 12. Thereupon the wedge 32 is entered between the halves 30, 31 and the projections 33, 34 of these halves are turned over to engage the end face of the wedge 32 and to retain the latter in position.

What I claim as new and desire to secure by Letters Patent of the United States is:

1. Bladed structure comprising a support forming an undercut groove with a notch and a recess in the bottom of the groove adjacent the notch, a plurality of blade and spacer members between the blades having portions engaging and filling the groove, the spacer member filling the notch having an extension located in the recess and engaging the end faces of adjacent members, at least one other spacer member be-

ing made in two halves to permit assembly with the support subsequent to assembly of the spacer member located in the notch, and means locking said halves to the support.

2. Elastic fluid turbine bucket wheel comprising a disk having an undercut groove forming a shoulder with a notch in the shoulder and a recess in the bottom of the groove adjacent the notch, a plurality of buckets having undercut bases engaging the shoulders and located in the 10

groove, and a spacer between each pair of adjacent buckets having an undercut portion engaging the shoulders and located in the groove, one of the spacers filling the notch having an extension located in the recess and engaging the end faces of adjacent buckets, two other spacers being made in two halves to permit assembly subsequent to the assembly of the notch spacer, and a wedge locking the two halves to the disk.

JAKOB NEUFELD.
